UNITED STATES PATENT OFFICE.

HOUSTON TAYLOR, OF BIRMINGHAM, ALABAMA.

DESIGN FOR A GUIDE FOR BUSINESS SYSTEMS.

46,654.

Specification for Design.

Patented Nov. 17, 1914.

Application filed September 2, 1914. Serial No. 859,928. Term of patent 14 years.

To all whom it may concern:

Be it known that I, HOUSTON TAYLOR, a citizen of the United States, residing at Birmingham, in the county of Jefferson and State of Alabama, have invented a new, original, and ornamental Design for a Guide for Business Systems, of which the following is a specification, reference being had to the accompanying drawing, forming part thereof.

The figure is a face view of a guide for business systems, showing my new design.

I claim:

The ornamental design for a guide for business systems, as shown.

HOUSTON TAYLOR.

Witnesses:

IVY E. SIMPSON,
RUTH SCOTT.
